UNITED STATES PATENT OFFICE

166,015

COMBINATION COIN AND CIGARETTE HOLDER

Nickolas P. Andrews, Chicago, Ill., assignor to Sinko Mfg. & Tool Co., a corporation of Illinois

Application October 10, 1951, Serial No. 16,897

Term of patent 14 years

(Cl. D52—2)

To all whom it may concern:

Be it known that I, Nickolas P. Andrews, a citizen of the United States, residing at Chicago, county of Cook and State of Illinois, have invented a new, original, and ornamental Design for a Combination Coin and Cigarette Holder, of which the following is a specification, reference being had to the accompanying drawing, forming a part thereof, in which:

Figure 1 is a front elevational view of a combination coin and cigarette holder, showing my new design; Fig. 2, a rear elevational view; Fig. 3, a side elevational view; Fig. 4, a top plan view; and Fig. 5, a bottom plan view.

I claim:

The ornamental design for a combination coin and cigarette holder, as shown.

NICKOLAS P. ANDREWS.
